UNITED STATES PATENT OFFICE.

SOFIA HAAG, OF FORT SHERIDAN, ILLINOIS.

HAND-LOOM.

1,335,163.

Specification of Letters Patent. Patented Mar. 30, 1920.

Application filed November 10, 1919. Serial No. 336,990.

(FILED UNDER THE ACT OF MARCH 3, 1883, 22 STAT. L., 625.)

To all whom it may concern:

Be it known that I, SOFIA HAAG, a citizen of the United States, stationed at Fort Sheridan, Illinois, have invented an Improvement in Hand-Looms, of which the following is a specification.

The invention described herein may be used by the Government, or any of its officers or employees in prosecution of work for the Government, or by any other person in the United States, without payment of any royalty thereon.

This invention relates to an improved loom and contemplates the provision of a device which may be used for weaving articles by hand, by inexperienced operators.

One object of the invention is to produce a hand-loom, which may be used not only to manufacture woven articles of value, but which also may be used to provide amusement.

Another object of this invention is to provide a hand-loom, which is capable of being used to produce a figured fabric, as for instance a twilled fabric, or one of a herringbone or diamond weave, as distinguished from the material produced by straight weaving. A cloth having these characteristics is the result of that kind of weaving in which the warp is manipulated to form successive sheds, differing from one another in the portions of the warp strands so parted.

Another object of the invention is to produce a hand-loom which is compact and light in weight which may be used by an operator who is partially incapacitated. In this connection, the present invention has proved of utility in hospitals and convalescent camps for soldiers, where some means of amusement is to be provided. The present hand-loom may be set up for use by a patient confined in bed, and, as it is easily operated by hand without the necessity of foot-treadles or like devices, it has been found to be of general application.

Still another object is to produce a loom of the simplest form which can be inexpensively produced and by which weaving may be done with the least complicated form of structure.

With these and other objects in view as will appear from time to time in the following specification and appended claims reference is now made to the accompanying

drawings for a better understanding of the invention.

In the drawings, Figure 1 is a view in longitudinal section of the device;

Fig. 2 is a front elevation;

Fig. 3 is a view in perspective of a detail of the warp and weft, showing the formation of the shed;

Fig. 4 is a front elevation of a modified form of the device;

Fig. 5 is a cross-section of the device illustrated in Fig. 4;

Fig. 6 is a cross-sectional view similar to Fig. 5 but showing the parts in different positions.

Briefly stated the invention contemplates a loom consisting of a pair of warp-carrying frames, relatively movable to produce the shed. The weft or filling is passed through the shed by hand either with or without the use of a shuttle or other device corresponding thereto.

In the simplest form of the device, there is provided a base 1 composed of triangular end pieces 2, 2, joined by a horizontal cross bar 3. Mounted upright in the base are posts 4, 4 supporting at their upper ends a horizontal frame 5. This frame 5 is rectangular in form consisting of side pieces 6, 6 and end pieces 7. The frame is open in the center for a purpose later to be described.

Mounted, pivotally at 8 and 9, on the base, is an inverted U-shaped frame movable from side to side as indicated in the dotted lines in Fig. 1. The frame consists of side pieces 10, 11 and cross piece 12.

To employ this form of device in weaving, the first operation is the stringing of the warp. Starting at the horizontal frame a strand of the warp is drawn around the side pieces and tied as at 15 to form a loop as shown at 13, Fig. 3. The strand is then brought downwardly, carried beneath the cross bar 3 of the base, and led upwardly, through the center of the horizontal frame to the cross-piece 12 of the inverted U-shaped frame to which it is attached as at 14. This procedure is repeated according to the width of fabric desired. It will be seen that each individual strand enters into and forms part of the warp in two places. One end of each strand is tied to the fixed horizontal frame, the other to the pivoted in-

verted U-shaped frame. This arrangement virtually divides the warp into two parts as indicated and it serves a useful purpose in the operation of weaving as will be 5 shown.

To start weaving, the pivoted frame is swung to one side as indicated in the dotted lines in Fig. 1. This separates the two portions of the warp to form a shed and the 10 weft or filling is introduced. The filling may be wound on some form of shuttle or simply passed through the shed in a ball-like mass. This feature is immaterial inasmuch as the filling is placed in position by 15 hand and may be handled in any way most convenient. Having passed a strand of filling through the shed, the pivoted frame is now moved as far as possible in the opposite direction and the filling brought back 20 through the new shed. The successive filling strands are laid closely against each other by the use of a comb, or by hand without the use of any instrument. This cycle of operations is repeated as often as may be 25 desired, determining, of course, the length of the product.

To weave a patterned fabric, by the introduction of threads of different colors, this is accomplished by cutting the filling strand, 30 tying the loose end to a convenient warp strand, then leading through the shed, the strand of the new or different colored material. The thread of the new color may be laid to make a stripe of any width as may 35 be desired.

To weave a particular figure into the fabric as shown in Fig. 2, the same method is employed, the different colored filling strands being laid in place to bring out the 40 outlines of the figure. It will be evident that in the figure shown, some of the dark colored filling threads will be quite short in length, in proportion to the width of the cloth. To make the fabric firm it is necessary 45 that the dark colored threads should be securely tied in and this is done by interlacing the ends of the short filling lengths with the adjacent warp-threads. The short filling ends are wound around an adjacent 50 warp strand once or twice and the loose end brought back between the warp strands, as far as it will go. This results in a firm fabric not likely to fray. The same procedure is followed when the ends of the filling 55 are to be cut, when the piece has been woven to the length desired.

It has also been found useful to prevent raveling of the filling by folding back the end and sewing, to form a narrow seam.

60 The production of a figured fabric is accomplished by the use of the modified form of the invention illustrated in Figs. 4, 5 and 6. The loom here shown differs from that in Fig. 1, only in that there is provided an 65 auxiliary movable frame to be used in con-

junction with the movable inverted U-shaped frame and the fixed horizontal frame.

Referring now to Figs. 4, 5 and 6, the device as modified consists of a base 1, composed of triangular end pieces 2, 2, joined by a horizontal cross bar 3. Mounted upright in the base are posts 4, 4, supporting a horizontal frame 5. This frame is rectangular in form, consisting of side pieces, 6, 6 75 and end pieces 7. The frame has an open center.

Mounted pivotally on the base at 8, 9, is an inverted U-shaped frame, movable from side to side. This frame is composed of side 80 pieces 10, 11 and a cross piece 12. It will be seen that this inverted U-shaped frame is mounted on the insides of the posts 4, 4 and the side pieces extend through, and to a point beyond the open center frame 5. 85

Pivoted mounted at 8, 9 on the outsides of the posts 4, 4, are posts 17, 18 supporting at their upper ends a horizontal rectangular open center frame 19, composed of side pieces 20, 20 and end pieces 21, 21. It will be seen that the movable frame 19 is mounted above the frame 5 but below the cross-piece 12 of the inverted U-shaped frame, which extends through the auxiliary frame 19, as shown. By the arrangement described, it will be seen that the new form of 95 loom has one fixed and two movable warp-carrying frames.

The warp is strung on the modified device in somewhat the same method as before. Starting at frame 5, a strand is drawn around the side pieces and tied to form a 100 loop as before. The end is then drawn down carried beneath the cross bar of the base and led upward through the open center of the frame 5, to the auxiliary frame 19, to which it is attached by a loop as in the case of frame 5. The next strand of the 105 warp is attached first to the auxiliary frame 19 by a loop, brought downwardly through the open center of frame 5 to the cross bar, carried beneath the cross bar and led upwardly through frame 5 and frame 19 to the cross piece 12 of the inverted U-shaped frame to which it is attached. The third 110 strand of the warp is strung in the same manner as the first, the fourth as the second. This procedure is continued according to the width of the fabric, it is desired to weave. 115

Weaving with the modified form of loom 120 may be done with the formation of a number of different sheds. For instance, with the auxiliary frame held at rest with relation to the fixed frame, the inverted U-shaped frame may be moved to the side position as indicated in Fig. 5 to form a shed through which the filling thread may be introduced. Again, the inverted U-shaped frame may be held stationary and the auxiliary frame swung to the side to produce a 125 130

shed. It is possible also to swing both the auxiliary and the U-shaped frames in unison from side to side. It is evident that the provision of an auxiliary movable frame permits of manipulation of the movable frames to form a variety of sheds, and obviously this permits of weaving fabrics of different textures, whereas in the simpler form of the device only straight weaving is possible.

10 As will be seen the art of weaving has been reduced by the use of this device to a series of extremely simple operations not necessitating a high degree of skill nor requiring any extensive instruction. The 15 most inexperienced operator may use the novel loom without difficulty, since there is no complicated mechanism to be handled.

It is to be understood that while the method of stringing the warp herein described is the method preferred as being simplest, it is evident that it is not necessary that each strand should be led beneath and around the horizontal cross-bar, but may be cut and attached thereto.

25 The use of the novel loom in hospitals and convalescent camps will be readily understood, to provide amusement as well as being capable to produce articles of general utility.

30 While it is not desired to limit the construction to the form shown, although that is the preferred type, it will be clear that the novel device is capable of further modifications, within the meaning and scope of 35 the appended claims.

What I claim as new and desire to secure by Letters Patent is:

1. In a device of the class described, a fixed warp carrying frame and a movable 40 warp carrying frame pivotally mounted thereon, said frames being adapted for relative movement to produce a shed.

2. In a device of the class described, a base, a pair of warp carrying frames mounted 45 thereon and relatively movable to produce a shed, and a warp having its ends attached to said base and to said frames.

3. In a device of the class described, a base, a pair of frames mounted thereon, a 50 warp having its ends attached to said base and to said frames, and means to produce relative movement of said frames to produce a shed.

4. In a device of the class described, a

base, a horizontal frame mounted thereon, 55 a vertical frame mounted on said horizontal frame, both of said frames being adapted to have warp threads attached thereto, and means to permit of the relative movement of said frames to produce a shed. 60

5. In a device of the class described, a base, a frame adapted to have warp threads attached thereto mounted thereon, and a second frame adapted to have warp threads attached thereto, partially encircling said 65 first-named frame, said frames being capable of relative movement to produce a shed.

6. In a device of the class described, a base, a frame adapted to have warp threads attached thereto, mounted thereon, and a 70 second frame adapted to have warp threads attached thereto pivotally mounted adjacent said first frame.

7. In a device of the class described, a base, a plurality of warp carrying frames 75 mounted thereon and capable of relative movement to produce a shed, and a warp having its ends attached to said base and to said frames.

8. In a device of the class described, a 80 base, a pair of spaced posts mounted thereon, a rectangular open-center warp-carrying frame mounted between said posts, and an inverted U-shaped warp-carrying frame pivotally mounted on said posts. 85

9. In a device of the class described, a base, a pair of spaced upright posts mounted thereon, a cross-bar in said base adapted for having a warp passed thereabout, a rectangular open-center frame mounted on said 90 posts, adapted for having the ends of a portion of said warp threads attached thereto, and an inverted U-shaped frame having its legs pivotally mounted on said upright posts, the cross-piece of said U being adapted to receive the ends of another portion of said warp threads, passing through said open-center frame. 95

10. In a device of the class described, a base, a plurality of open-center, warp-carrying frames mounted thereon, an inverted U-shaped warp-carrying frame pivotally mounted adjacent thereto, said frames being capable of relative movement to produce a shed, and a warp having its ends attached 105 to said base and to said frames.

SOFIA HAAG.
